UNITED STATES PATENT OFFICE.

JOHN J. REINHOLD, OF MARIETTA, PENNSYLVANIA.

ELECTRIC FAN.

Application filed February 3, 1922. Serial No. 533,743.

To all whom it may concern:

Be it known that I, JOHN J. REINHOLD, a citizen of the United States, and a resident of Marietta, county of Lancaster, State 5 of Pennsylvania, have invented certain new and useful Improvements in Electric Fans, of which the following is a specification.

This invention relates to electric fans in which the air is directed through a circular path, principally for the purpose of obtaining 10 a greater distribution of the air than that obtained when the axis of the fan is held stationary, or when the fan is merely oscillated laterally in the usual manner.

15 The object of this invention is to provide a simple and compact arrangement for imparting a circulatory motion to a power transmitting or producing device, for instance an electric motor as described in the 20 following specification, and utilizing the power transmitted or produced by said device for operating said arrangement.

This invention will be more fully understood from the following description, taken 25 in connection with the accompanying drawing, in which similar numerals refer to similar parts throughout the several views.

Fig. 1, represents a practical embodiment 30 of my invention; certain portions of which are shown in sectional view.

Fig. 2, is a sectional view of Fig. 1, taken on line 2—2.

With reference to the drawing, 3 represents an electric motor which carries the fan 35 4. The motor is carried by the base 9 through a fork shaped bracket 5. The motor is provided with two pivot pins 6 (one only being shown in the drawing) upon which the motor may rock as indicated by 40 the arrow 7. The bracket 5 is provided with a stem 8 the same being adapted to freely turn in the base 9; this permits free lateral movement of the motor on a vertical axis passing through said stem. The set collar 45 10 should be fixed to the stem 8 through a set screw, or otherwise, to prevent the bracket 5 from separating from the base 9, however it must not interfere with free rocking movement of the bracket relative to the base.

50 A bracket 25 forms part of the motor casing and carries a stud 24. An internal worm gear 23 is free to rotate on the stud 24 and carries a pin 12, thereby forming a crank element. A bracket 14 is fixed to the

base 9 through the screws 15; the upper end 55 being adapted to form a bearing for the pin 12.

It is apparent that since the bracket 14 is fixed to the base 9 and thereby held stationary, the pin 12 is also held stationary, 60 or in other words, held against all movement other than a rotating movement upon its own axis; therefore if by any means efforts are applied to rotate the gear 23 on the stud 24, this gear will in fact rotate around the 65 axis of the pin 12 with the result that the stud 24 is caused to move through a circular path around the axis of the pin 12. Since the stud 24 is fixed to the bracket 25 which forms part of the motor casing, then 70 this end 11 of the motor is also moved through a circular path around the axis of the pin 12. It is to be observed that the motor is free to respond to any efforts to move the same in this fashion, because it is 75 free to rock on a vertical axis running through the stem 8, and also on a horizontal axis running through the point pin 6.

As a transmission means for rotating the gear 23 from the energy supplied by the 80 motor, I provide a worm thread 17 on the end of the armature shaft 16. A shaft 19 is carried by the housing 21 and may be held 85 against lengthwise movement by slightly riveting the ends 20. The worm wheel 22 and worm gear 18 comprise one unit which 90 is free to rotate on the shaft 19. The worm gear 18 is adapted to mesh with the worm thread 17, and the worm wheel 22 with the internal worm gear 23. When the armature shaft 16 rotates it drives the worm gear 18, this of course causes the worm wheel 22 to 95 rotate which finally drives the worm gear 23.

From the foregoing description it may be 100 seen that while the motor is operating to rotate the fan it at the same time actuates the crank element to effect a circulatorious motion to the motor, with the result that the air passing through the fan is directed through a circular path.

Having thus described my invention, what I claim as new and desire to secure by Letters Patent is as follows:

1. In an electric fan, comprising a motor, 105 a fan driven by said motor, a base for carrying the motor, means whereby said motor may turn on a vertical axis and also on a horizontal axis, a crank element adapted to
